COMBINED TABLE AND CANE MILL DISPLAY UNIT

Hayner R. Spencer, Granite Falls, N. C.

Application February 20, 1957, Serial No. 44,928

Term of patent 14 years

(Cl. D34—15)

Figure 1 is a perspective view looking at one side of the combined table and cane mill display unit with leg portions of the table broken away for convenience of illustration;

Figure 2 is a perspective view looking at the other side of the combined table and cane mill display unit with leg portions of the table broken away for convenience of illustration.

The dominant features of the design reside in the portions shown in full lines.

I claim:

The ornamental design for a combined table and cane mill display unit, substantially as shown and described.

No references cited.
